Primary Examiner — Sheryl Lane*Assistant Examiner* — Nicole C Shiflet(74) *Attorney, Agent, or Firm* — Ohlandt, Greeley, Ruggiero & Perle, L.L.P.**CLAIM**

The ornamental design for a burner cover, as shown and described.

DESCRIPTION

FIG. 1 is a perspective view of the burner cover of the present disclosure.

FIG. 2 is a first elevation view of the burner cover of FIG. 1;

FIG. 3 is a second elevation view of the burner cover of FIG. 1;

FIG. 4 is a top plan view of the burner cover of FIG. 1; and, FIG. 5 is a bottom plan view of the burner cover of FIG. 1. The broken lines in the drawings depict environmental structure and boundaries, and form no part of the claimed design.

1 Claim, 4 Drawing Sheets(56)
